(57) **CLAIM**

The ornamental design for a battery powered screwdriver, as shown and described.

DESCRIPTION

FIG. 1 is a right side isometric view of a battery powered screwdriver showing my new design;

FIG. 2 is a left side isometric view thereof;

FIG. 3 is front elevational view thereof;

FIG. 4 is a right side elevational view thereof;

FIG. 5 is a top plan view thereof;

FIG. 6 is a left side elevational view thereof;

FIG. 7 is a rear view thereof; and,

FIG. 8 is a bottom plan view thereof.
